UNITED STATES PATENT OFFICE.

CHARLES M. REYNARD, OF MCKEESPORT, PENNSYLVANIA, ASSIGNOR TO MCKEESPORT TIN PLATE COMPANY, OF MCKEESPORT, PENNSYLVANIA, A CORPORATION OF PENNSYLVANIA.

APPARATUS FOR CLEANING TIN PLATES.

1,136,270.

Specification of Letters Patent. Patented Apr. 20, 1915.

Application filed March 28, 1914. Serial No. 827,945.

To all whom it may concern:

Be it known that I, CHARLES M. REYNARD, a citizen of the United States, and resident of McKeesport, in the county of Allegheny and State of Pennsylvania, have invented a new and useful Improvement in Apparatus for Cleaning Tin Plates; and I do hereby declare the following to be a full, clear, and exact description thereof.

10 My invention relates to apparatus for cleaning tin-plates.

In the manufacture of tin-plates, the sheets are passed from the tinning-pot where they receive their coating of tin to cleaning apparatus to remove the oil and the dirt mixed with the same, which may adhere to the plate as it comes up through the palm oil which covers the tin in the tinning pots. In order to remove this oil or grease the 20 plates are passed through rolls which revolve in a suitable receptacle containing saw-dust, bran or other mixture which will remove this oil or grease as the plates pass through it.

25 The object of the present invention is to provide apparatus of this character in which the saw-dust, bran or other material, which is carried out of the receptacle by the movement of the plates through the body of material, is discharged into a suitable receptacle below, so that it may be conveyed upwardly and discharged again into the receptacle, by being evenly distributed across the rolls contained therein, and the invention 35 comprises the novel features hereinafter set forth and claimed.

In the drawings, Figure 1 is an end view of my improved apparatus, and Fig. 2 is a longitudinal sectional view.

40 The numeral 2 designates a suitable stand or frame which supports the box or receptacle 3 containing the bran, saw-dust or other mixture, 4, for cleaning the sheets. This frame also forms the support for the driving 45 mechanism for driving the rolls and the conveyers. This driving mechanism consists of the pulley 5 which is mounted on the shaft 6 journaled in bearings in the bracket 7 and the stand or frame 2. Rotary movement is 50 imparted to the pulley 5 by means of a belt leading from a suitable motor or engine. The shaft 6 has the pinion 8 which meshes with the gear-wheel 9 on the stub-shaft 10. A pinion 11 on the stub-shaft 10 communicates rotary movement to a train of gears 12

which drive the pairs of rolls 13 in opposite directions. These rolls 13 are mounted in suitable bearings in the upper part of the frame 2, and rotate within the box 3, the first four pairs of rolls rotating in the cleaning mixture 4, and the last two pairs being outside of said cleaning material, as indicated in Fig. 2.

The box 3 is provided with the rear-wall 14 which extends up to a point just below the pass of the rolls, and said rear wall confines the cleaning material up to that point. The front wall 15 of the box 3 has the slot 16 for the entrance of the plates to be passed through the rolls. The bottom plate 17 of the box 3 is removable, being arranged to slide in guides and is provided with the handle 18 by means of which said bottom may be inserted or withdrawn.

The frame 2 contains the receptacle 19 with the inclined walls 20, and at the bottom of said receptacle, extending transversely of the frame 2 is the spiral conveyer 21 carried by the shaft 22. This shaft 22 is journaled in suitable bearings in the frame 2 and at 50 one end of said shaft is the sprocket wheel 23. A chain 24 engages said sprocket wheel, said chain leading from the sprocket wheel 25 on the shaft 6. In this way rotary movement is imparted to the spiral conveyer 21.

The spiral conveyer 21 extends out into the inclined passage 26 which communicates with the upwardly extending passages 27. A bevel pinion 28 on the shaft 22 meshes with a bevel pinion 29 on the shaft 30 which 90 carries the spiral conveyer 31 working in the passage 27. The upper end of the passage 27 communicates with the curved passageway 32 which is formed of an elbow section 33 connected to the passage 27 by the collar 34 which is adapted to turn on the upper end of the passageway 27.

The curved passageway 32 discharges into the hopper member 35 extending transversely of the frame 2, said hopper member being supported on the swinging bracket 36, which is hinged to the box 3 at 37. The bottom of the hopper 35 is provided with the longitudinally extending slot or opening 38. A slideable cover 39 controls the size of the opening 38, said cover being held in any desired position by means of the set-screws 40.

Contained within the hopper 35 is the spiral conveyer 41 mounted on the shaft 42. This shaft 42 is provided with the sprocket 110

wheel 43, and a chain 44 connects said sprocket wheel up with the sprocket wheel 45 on the shaft 46, which is driven by the train of gearing 12.

5 The plates to be cleaned, as they come from the tinning-pots, are inserted into the opening 16 at the front end of the box 3, and are taken up by the first pair of rolls, and are fed forward through the succeeding 10 rolls passing through the bran, saw-dust or other cleaning material 4, and as the plates pass through and over the end wall 14, a certain amount of cleaning material will be carried over with said plate, and this will 15 fall down into the receptacle 19 and into position to be operated on by the spiral conveyer 21. This conveyer 21 conveys this cleaning material into the inclined passage 26, where it is forced along into the passage 20 27 to be taken up by the spiral conveyer 31 and discharged at the upper end thereof into the passage 32, whence it is discharged into the hopper 35. The spiral conveyer 31 in said hopper moves it along said hopper 25 until it reaches the opening 38, whence it is discharged into the box 3 at a point adjacent to the first pair of rolls 13. By having the inclined passage 26, there is no clogging up of the material but it is forced up the inclined passage 26 to be engaged by the spiral conveyer 31 in the passage 27. In this manner I provide for the recovery of 30 the cleaning material which is carried from the cleaning box by the plates in their passage through the rolls, and this cleaning material is conveyed rapidly back to the point where it is discharged into the cleaning box, so that the cleaning box is constantly being replenished and interruption 35 40 in the work due to the replenishing of the cleaning box is avoided, while at the same time cleaning material is so evenly distributed in the box as to prevent the collection of cleaning material in piles at any one point.

When the cleaning material has become saturated with oil and grease, and it is necessary to remove such cleaning material and introduce a clean supply into the box, the 45 sliding bottom 17 is withdrawn, which allows the material to drop into the receptacle 19 and it is conveyed off by the spiral conveyers in the manner above described, but in order not to return it again to the hopper 50 55 per 35 the elbow 33 is turned around in position to discharge this material in another direction, and when all the material has been removed in this way, the slide 17 is inserted. The bracket 36 is then swung 60 back together with the hopper 35 which gives easy access to the box for the introduction of a new lot of cleaning material.

What I claim is:

1. In apparatus for cleaning tin plates, 65 the combination with a suitable frame, of a

receptacle for containing the cleaning material, power driven rolls mounted in said receptacle, a second receptacle below said first named receptacle, a hopper member above said first named receptacle having an elongated opening extending across said first named receptacle, a conveyer in said hopper member, and means for conveying the material from said second named receptacle to said hopper member.

70

2. In apparatus for cleaning tin plates, the combination with a suitable frame, of a receptacle for containing the cleaning material, power driven rolls mounted in said receptacle, a second receptacle below said first named receptacle, a hopper member having an elongated opening extending across said first named receptacle, an adjustable cover for said opening, a conveyer in said hopper member, and means for conveying the cleaning material from said second named receptacle to said hopper member.

75

3. In apparatus for cleaning tin plates, the combination with a suitable frame, of a receptacle for containing the cleaning material, power driven rollers mounted in said receptacle, a second receptacle below said first named receptacle, a conveyer in said last named receptacle, an upwardly inclined passage communicating with said second receptacle, and into which said conveyer extends, an upwardly extending passage connecting with said inclined passage, a conveyer in said upwardly extending passage, a hopper member at the upper end of said upwardly extending passage and communicating therewith, said hopper member having a longitudinally extending opening over said first receptacle, and a conveyer in said hopper member.

80

4. In apparatus for cleaning tin plates, the combination with a suitable frame, of a receptacle for containing the cleaning material, power driven rollers mounted in said receptacle, a second receptacle below said first receptacle, a hinged bracket on said first receptacle, a hopper member mounted on said bracket above said receptacle, and means for conveying the cleaning material from said second receptacle to said hopper.

90

5. In apparatus for cleaning tin plates, the combination with a suitable frame, of a receptacle for the cleaning material, power driven rollers mounted in said receptacle, a second receptacle below said first receptacle, a conveyer in said second receptacle, an upwardly extending passage communicating with said receptacle, into which said conveyer extends, a conveyer in said upwardly extending passage, a movable elbow section at the upper end of said upwardly extending passage, and a hopper member into which said elbow is adapted to discharge, said hopper being arranged above said first receptacle.

130

6. In apparatus for cleaning tin plates, the combination with a suitable frame, of a receptacle for containing cleaning material, power driven rollers mounted in said receptacle, a second receptacle below said first receptacle, a spiral conveyer in said second receptacle, an upwardly extending passage communicating with said second receptacle, a spiral conveyer in said upwardly extending passage, a hopper member communicating with the upper end of said upwardly
- extending passage, a spiral conveyer in said hopper, and said hopper having an elongated opening extending across said first receptacle.
- 15

In testimony whereof, I the said CHARLES M. REYNARD have hereunto set my hand.

CHARLES M. REYNARD.
